CHILD'S HANDBAG

Barnett David, Brooklyn, N. Y.

Application March 26, 1953, Serial No. 24,210

Term of patent 7 years

(Cl. D87—3)

To all whom it may concern:

Be it known that I, Barnett David, a citizen of the United States, residing in Brooklyn, in the county of Kings and State of New York, have invented a new, original, and ornamental Design for a Child's Handbag, of which the following is a specification, reference being had to the accompanying drawing, forming part thereof.

Fig. 1 is a front view of a child's handbag showing my new design,

Fig. 2 is the rear view thereof,

Fig. 3 is another front view of the design shown in Figs. 1 and 2 with the strap member in unbuttoned position and the telephone member in suspended position, and

Fig. 4 is a side view of the handbag shown in Figs. 1, 2 and 3.

I claim:

The ornamental design for a child's handbag, substantially as shown.

BARNETT DAVID.
